United States Patent Office

Des. 227,532

Patented July 3, 1973

227,532

CUP

Niels Refsgaard, also known as Niels Refsgaard Andersen,
Ishøj Per Taastrup, Denmark, assignor to Dansk De-
signs Ltd., Mount Kisco, N.Y.

Filed Jan. 17, 1972, Ser. No. 218,632

Term of patent 14 years

Int. Cl. D7—01

U.S. Cl. D7—9

FIG. 1

FIG. 2

FIG. 3

FIG. 4

FIG. 5

FIG. 6

FIG. 1 is a top plan view of a cup embodying my novel design;

FIG. 2 is a front elevational view thereof, the rear elevational view being a mirror image thereof;

FIG. 3 is a left side elevational view thereof;

FIG. 4 is a right side elevational view thereof;

FIG. 5 is a bottom plan view thereof; and

FIG. 6 is a sectional view taken along line 6—6 of FIG. 1.

I claim:

The ornamental design for a cup, as shown and described.
